INVENTOR

UNITED STATES PATENT OFFICE

129,402

DESIGN FOR AN IDENTIFICATION TAG FOR A BRACELET OR THE LIKE

Cyril Bernard Schindler, New Orleans, La.

Application December 16, 1940, Serial No. 97,357

Term of patent 7 years

To all whom it may concern:

Be it known that I, Cyril Bernard Schindler, a citizen of the United States, residing at New Orleans, in the parish of Orleans and State of Louisiana, have invented a new, original, and ornamental Design for an Identification Tag for a Bracelet or the like, of which the following is a specification, reference being had to the accompanying drawing, forming a part thereof.

Fig. 1 is a front elevational view of an identification tag showing my new design; and
Fig. 2 is a top plan view thereof.

I claim:

The ornamental design for an identification tag for a bracelet or the like, as shown.

CYRIL BERNARD SCHINDLER.
